(57) **CLAIM**

The ornamental design for a body sculpting hand piece hanger, as shown and described.

DESCRIPTION

FIG. 1 is a front perspective view of a hanger for holding the hand pieces of a body sculpting apparatus, showing an embodiment of my new design;

FIG. 2 is a bottom perspective view of the hanger shown in FIG. 1;

FIG. 3 is a top view of the hanger shown in FIG. 1;

FIG. 4 is a bottom view of the hanger shown in FIG. 1;

FIG. 5 is a side view of the hanger shown in FIG. 1;

FIG. 6 is a front view of the hanger shown in FIG. 1;

FIG. 7 is a rear view of the hanger shown in FIG. 1;

FIG. 8 is a front perspective view of an alternative embodiment of our design, having a slightly wider opening;

FIG. 9 is a bottom perspective view of the hanger shown in FIG. 8;

FIG. 10 is a top view of the hanger shown in FIG. 8;

FIG. 11 is a bottom view of the hanger shown in FIG. 8;

FIG. 12 is a side view of the hanger shown in FIG. 8;

FIG. 13 is a front view of the hanger shown in FIG. 8; and,

FIG. 14 is a rear view of the hanger shown in FIG. 9.

In each embodiment, the right and left sides are identical to each other.

1 Claim, 10 Drawing Sheets
